UNITED STATES PATENT OFFICE.

CONOVER T. SILVER, OF NEW YORK, N. Y.

DESIGN FOR A COMBINED AUTOMOBILE RUNNING-BOARD AND FENDER.

52,409.

Specification for Design.

Patented Sept. 10, 1918.

Application filed February 28, 1917. Serial No. 151,589. Term of patent 14 years.

To all whom it may concern:

Be it known that I, CONOVER T. SILVER, a citizen of the United States, and a resident of the city of New York, borough of Manhattan, county and State of New York, have invented a new, original, and ornamental Design for a Combined Automobile Running-Board and Fender, of which the following is a specification, reference being had to the accompanying drawing, forming a part thereof.

Figure 1 is a side elevation of an automobile running board showing my new design;

Fig. 2 is a plan view of Fig. 1;

Fig. 3 is a front view of Fig. 1;

Fig. 4 is a rear view of Fig. 1;

Fig. 5 is a sectional view on the line 5—5 of Fig. 1;

Fig. 6 is a sectional view on the line 6—6 of Fig. 1; and

Fig. 7 is a sectional view on the line 7—7 of Fig. 1.

I claim:

The ornamental design for a combined automobile running board and fender as shown.

CONOVER T. SILVER.

Witnesses:

J. M. LOWENSTEIN,

H. E. REID.
